UNITED STATES PATENT OFFICE.

JOHN W. DARLEY, JR., OF BALTIMORE, MARYLAND, ASSIGNOR OF ONE-HALF
TO MICHAEL HOLZMAN, PHILIP HAMBURGER, AND LEON HAMBURGER,
OF BALTIMORE, MARYLAND.

PIANO-ACTION.

SPECIFICATION forming part of Letters Patent No. 687,608, dated November 26, 1901.

Application filed June 2, 1899. Serial No. 719,096. (No model.)

To all whom it may concern:

Be it known that I, JOHN W. DARLEY, Jr., a citizen of the United States, residing at Baltimore, in the State of Maryland, have invented certain new and useful Improvements 5 in Piano-Actions; and I do hereby declare the following to be a full, clear, and exact description of the invention, such as will enable others skilled in the art to which it appertains to make 10 and use the same.

My invention relates to improvements in piano-actions, and especially in those actions known as "repetition" actions, which are designed to enable the operator to sound the 15 same note repeatedly in rapid succession and at the same time preserve that quality known as the "touch," which is very essential for the satisfaction of the performer.

Musicians who have played on an upright 20 piano provided with my improved action have found that they could produce the required modulations in a satisfactory manner, as the keys, although light to the fingers and playing freely, do not drop away from the fingers 25 of the player, as with actions of the construction now most commonly in use on upright pianos. I attribute this improved effect to the fact that the hammers are subject to an approximately equal retraction, corresponding 30 in this regard to the hammers of the grand piano.

The present invention is especially intended to cover certain improvements upon the device described in my application, Serial No. 35 606,730, filed September 23, 1896.

Reference is had to the accompanying drawings, wherein the same parts are indicated by the same letters of reference throughout the several views.

40 Figure 1 represents a side elevation of one of my improved piano-actions as it is mounted in the piano, the bars or rails which support the several parts of the said action being shown in section, but the framing supporting 45 the said rails being omitted for the sake of clearness in the drawings. In this view the parts are shown in their normal position when the key is at rest. Fig. 2 is a similar view to Fig. 1, but shows the parts in the position 50 they assume after the key has been struck.

Fig. 3 is a detail view of the hammer-spring. Fig. 4 represents a side view of the supporting-frame for the various rails, and Fig. 5 represents a front view of the same. Fig. 6 is a detail view, in front elevation, showing the 55 bifurcated front end of the jack-lever, a part of the abstract, and the stop on the jack and the relation of these parts to each other. Figs. 7 and 8 are detail views of the spring for controlling the damper-levers and the connection 60 of the said spring with the supporting-rail C.

A designates the base-board, upon which the several parts of the action are mounted, and B C designate the supporting-rails, which are secured to a suitable form of frame, such 65 as that shown in Figs. 4 and 5, and arranged parallel with each other and with the base-board A.

E designates the soft-pedal rail, which is supported by the wire arms e, one of which 70 is shown in Figs. 4 and 5, which arms are connected with the soft pedal in any well-known manner, and the rail E is arranged to rest normally against the padded ends of the screws R⁶ when the soft pedal is not in use. 75

The various rails and other parts of the piano-action are faced with felt or other suitable material wherever they are likely to be struck by any of the moving parts, and all centers are bouched with cloth in the usual 80 well-known way, the effect of the whole being to prevent rattling and to deaden all sounds except of the strings which have been struck.

x designates one of the strings of the piano. 85

F designates the key, pivoted upon the base-board, as at f, and having the usual cushions beneath all its points of contact with the framework of the piano.

The abstract H is hung to the supporting- 90 rail C by a three-arm jack-lever I and to the lower rail B by a straight lever K, and the said abstract is provided at its lower end with a foot h, which is suitably padded and rests upon the head of the screw f' in the inner end 95 of the key-lever F.

The flange R' (see Fig. 5) of the metal frame R, to which the rail B is screwed, may be provided with slots r' for the retaining-screws, if desired, so that the rail B may be moved 100

up or down to eliminate slip between the screw f' and the pad h^6 , when an escutcheon-pin r^2 may be driven through a hole in the flange R' into the rail B , thus preventing displacement of said rail.

5 One side of the foot h is extended and padded on its upper side, as at h' , to make contact with a wire f^2 , which extends upward from the key and over the said end of the 10 foot h to prevent the abstract from separating from the screw f' . This wire is bent down on the cushion h' by a suitable tool after the whole action is regulated, and when the tool is removed the slight resiliency of said wire 15 causes it to spring back and give the small amount of play required between it and said cushion h' .

The front toe R^5 of the frame R is secured to the base-board A in rear of a vertical line 20 drawn through the point of contact between the key and the foot h of the abstract, as shown in Fig. 4. This construction enables the frame R to be tilted forward on the toe R^5 for the purpose of removing the same, 25 which movement will move the foot h forward and out of engagement with the screw f' and the wire f^2 . To allow of this movement, no readjustment of the screw f' is necessary, for the abstract will simply move slightly upward, so that no cramping effect will exist 30 between the foot of said abstract and the screw f' .

To the upper side of the supporting-rail C is secured a cross-piece c , in one end of which 35 is pivoted, as at c' , the hammer-butt M , from which extends the stem M' , carrying the hammer M^2 . When in the normal position, the stem M' rests upon the hammer-rail E , which is padded to receive it. A depending lug m 40 is formed on the lower front corner of the hammer-butt, cushioned, as shown at m^x , to receive the thrust of the jack N . A tailpiece m' depends from the other lower corner of the hammer-butt and is cushioned, as at m^0 , 45 to receive the rear side of the head n of the jack N when the latter passes off of the lug m . The jack-lever I is pivoted to the supporting-rail C , as at i , and has the arms i' , i^2 , and i^3 , the abstract H being pivoted to the arm i' , as 50 at i^0 . The jack N is pivoted at its lower end to the arm i^2 of the jack-lever I and extends upward at an angle to the abstract, its upper end or head n normally resting beneath the lug m on the hammer-butt, as shown in Fig. 55 1. A recovery-spring O is mounted in the abstract H and is connected with the jack N by a flexible connection O' , the tension of the said spring being adjustable by means of the screw O^2 . It will be noticed that the flexible 60 connection O' forms an acute angle with the line drawn through the point of its attachment to the spring O and the fulcrum of said spring and that as the jack is flexed this angle increases to a right angle, the object of this construction being to increase the effect 65 of the recovery-spring O upon the hammer-butt when the hammer rebounds from the

spring while the key is held down. The tendency of the recovery-spring O is to draw the jack N toward the abstract H , the movement 70 of the jack in this direction being limited by a cushioned stop h^2 , adjustably connected to the said abstract. The center i^0 , where the abstract is pivoted to the jack-lever I , is so located with reference to the center i that the 75 top of the jack N , guided by the fulcrum h^2 , moves through substantially the same locus as the abutting surface of the lug m of the hammer-butt M , against which the jack thrusts while driving the hammer to the 80 string, the object of this being to prevent slipping and consequent friction between these parts. An arm N' is secured to the lower part of the jack N (above its pivot) and extends forward and downward partially around the 85 abstract and is provided at its end with a downwardly-projecting and adjustable stop n' . The bifurcated arm i' of the jack-lever I extends beyond the abstract and is provided with a cushion i^4 , arranged to strike the stop 90 n' , as will be hereinafter explained.

A flat spring D' (shown in detail in Fig. 3) is secured in the rail D and bears at its lower end against a cushioned nose m^2 on the hammer-butt M . The rail D is formed of two 95 sections d and d^2 , preferably glued together with the ends of the springs D' between them. They may be screwed together after being glued, if additional strength is desired. The frame R (see Fig. 4) is provided, as at r^4 , with 100 a round nose, which fits into a slightly-rounded groove in the section d . Screws d^1 , d^7 , passing through the flange R^4 of the frame R , serve to retain the rail D in place and also permit of the adjustment of the springs D' , 105 for by loosening the screw d^7 and tightening the screw d^6 , the tension of the springs D' may be increased, and vice versa. The pad d^3 , which serves as a stop for the damper-wire p , is mounted upon a separate wood strip 110 d^0 , which is screwed to the rail D , appropriate liners being placed between. By varying the thickness of these liners the pad d^3 may be adjusted independently of the springs D' . (See Fig. 3.) This spring D' is tapered, so as 115 to be smaller at its lower end, which rests against the nose m^2 . The enlarged head d' is to provide a good wearing-surface against the base m^2 and also to give sufficient weight on the end of the spring, so that if it became 120 loose it could not vibrate in unison with a corresponding tone that might be sounded on the piano. The office of the spring D' is to aid the hammer retraction, as when the hammer is in its raised position it is almost directly above its pivotal point c' and gravity has very little effect upon it. This spring D' is so arranged that it will exert its greatest tension when the force of gravity is at the minimum and will decrease its tension approximately in proportion as the force of gravity increases.

In practice I employ the same thickness of material for the springs throughout, but con-

struct them of three different widths and use the smallest in the treble-section, the largest in the bass-section and the medium size in the middle section of the piano. Starting 5 with the highest treble-hammer I use for the spring D' thereon a spring of such a profile as to increase the retraction on the hammer at the string to about twenty per cent. above what the retraction on the hammer amounts 10 to when said hammer is in its position farthest from the string. Thus when the hammer is at the string we have a certain retraction thereon which decreases as the hammer moves away from the string, and this, in connection 15 with the fact that the tension of the spring O increases as the jack is flexed by the hammer's rebound, insures a quick recovery of the hammer, for the farther said hammer rebounds the more power the spring O has 20 thereon. The springs D', made as just explained, are used from the highest treble-hammer down to that hammer where, owing to the increasing size and weight of the hammers as we go toward the bass-section, the retraction 25 becomes equal throughout said hammer's range of movement, and then the middle-size spring is used on the next lower hammer, which increases the retraction on this hammer when it is at the string to, say, about ten 30 per cent. above what the retraction amounts to when said hammer is away from the string, and this spring is used until that hammer is reached where the retraction again becomes constant, as before explained. I then use the 35 largest-size spring to give about ten per cent. more retraction when the next lower hammer is at the string than it gives when said hammer is away from the string and use this spring to the end. More than three different 40 sizes of springs may be employed, if desired. Thus in the treble-section, where great rapidity is desirable, we have more retraction when the hammer is at the string than we have when the hammer is at its farthest point 45 therefrom, and in other portions of the piano the hammer retraction is approximately equal.

Projecting rearwardly and upwardly at an angle from the hammer-butt is an arm M³, carrying a back-check M⁴, which is padded, as 50 shown. To the upper end of the abstract H is secured, by means of a wire h³, a back-check H', suitably padded and arranged to move as the abstract moves upward into position to engage the counter-check M⁴ as the hammer 55 rebounds after the stroke and to hold the hammer from further movement so long as the key is held down. This position is shown in Fig. 2.

A wire h⁴ extends from the upper end of 60 the abstract over the lower rear corner of the hammer-butt, which is padded, as at m³, and the said arm striking the pad m³ serves to assist in throwing the hammer back quickly, when the key is released suddenly. 65 The wire h⁴ is to be adjusted so that it just touches the pad m³ when the soft pedal is depressed.

P designates the damper-lever, which is pivoted on the rear end of the cross-piece c and has a stem p extending upwardly from its upper end, carrying the damper P', which is of the usual construction and adjustable upon the stem p. A spring p' is secured to the cross-piece c, preferably by the same screw that holds the said cross-piece to the rail C, and is bent upward to press against the rear side of the damper-lever P and hold the damper normally against the string x. The spring p' (see Figs. 7 and 8) is formed of sheet metal, bent as at p⁴. The piece c is 80 grooved, as shown at c⁸, to fit the lower end of spring p' and prevent its turning, the lower end p⁵ of the said spring being fitted in the said groove c⁸ and held therein by the screw c⁷. The lower end of the damper-lever extends 85 forward and is cushioned, as at p², to engage a spoon i⁵, which extends upwardly from the arm i³ of the jack-lever I. When the abstract is raised, as in striking the key, the pressure of the spoon i⁵ will cause the damper to leave 90 the string, and the latter will then be free to vibrate until the key is released, as will be readily understood.

The rod Q is operated by the loud pedal of the instrument and serves to throw all of the 95 dampers off at the same time.

The operation of the device is as follows: When the key is pressed downward, the screw f' will throw the abstract H upward, causing its two pivots to move, respectively, 100 in the arcs of circles about the pivots of the levers I and K, the body of the abstract moving slightly toward the front. The upward movement of the arm i³ of the lever I will press the jack N upwardly against the lug m on the 105 hammer-butt, thus throwing the hammer toward the string. Before the hammer strikes the string the cushion i⁴ on the arm i³ of the jack-lever I will strike the stop n' on the arm N', causing the jack to move in the arc of a circle about the pivot i of the lever I. This will cause the head n of the jack to pass off of the lug m into the recess between the lugs m and m', as shown in Fig. 2, this movement being 115 called the "release," while the momentum of the hammer will cause it to strike the string and rebound, assisted by the spring D', to the position shown in Fig. 2. When the end n of the jack N passes off of the lug m, it will strike the tailpiece m', and thus assist the 120 hammer to rebound; but this rebound will be checked by the counter-check M⁴ coming into contact with the back-check H', which has moved upward to meet it. Thus the hammer will be held firmly by the pressure of the 125 counter-check M⁴ on the back-check H' as long as the key is held down. When the key is released, the first effect of the downward movement of the abstract and jack-lever I will release the counter-check M⁴ and allow 130 the recovery-spring O to draw the jack toward the abstract, causing the end n of the jack to pass under the lug m on the hammer-butt, thus placing the parts in position to

make another stroke, even before the hammer has fallen against the hammer-rail or the key and abstract have fully returned to their normal positions. It is evident that 5 the effective distance from the pivot C' at which the force of the key operates is the perpendicular distance from the pivot C' to the prolongation of the line passing through the pivot C² of the jack and the point of contact 10 of said jack with the lug m; also, that the effective distance from the pivot C' at which the force of the recovery-spring O operates is the distance from the pivot C' to the point of contact of the inclined face of the jack 15 with the lug m, since in the release position of the jack said inclined face is practically on a radial line to said pivot C'. As it is evident that this latter distance is greater than the former, it follows that the force of the recovery-spring can be proportionally less than 20 what it would have to be if it acted at the same effective distance from the pivot of the hammer as the key operates, as has been the custom to arrange it heretofore. The spring 25 D' will assist the hammer to rebound promptly and start backward immediately upon the release of the key, and the tension of this spring is so adjusted, as before explained, that when the hammer-stem M' is in an approximately 30 vertical position the spring will exert its greatest strength; but as the hammer falls back toward the hammer-rail the tension of the spring will decrease until very little pressure is exerted. By the use of the nose m² 35 for the hammer-spring D' to bear against a much more accurate and constant point of application for the spring is obtained, for with the end of the spring bearing in the slot, as usual, a slight lengthening and shortening of 40 the spring will cause a considerable change in its point of application on the hammer-butt, and so may cause great irregularity in the touch of the adjacent keys. As the hammer moves toward the string the spoon i' on 45 the lever I will move the damper away from the string, as will be readily understood.

The recovery-spring is so mounted, as before explained, that in the first part of the movement of the jack during release it will 50 exert very little pull; but after the arm i' has acted upon the stop n' and throws the jack rearwardly the pull of this spring will increase as the hammer rebounds. This also causes the 55 spring to exert greater force on the jack the more it is flexed, thus causing it to pass under the lug m or "recover" promptly, and hence the recovery-spring is always able to bring the jack under the hammer ready for another blow, and this effect is entirely in- 60 dependent of the position of the key and hammer.

The herein-described invention provides a simple, effective, and durable repetition piano-action adapted to enable the operator to 65 sound the same note in rapid succession and with small elevations of the key, and it also gives the performer thorough control of the

expression while maintaining that desirable but almost indescribable element well known to musicians as the "touch" of the instrument. 70

Having thus described my invention, what I claim, and desire to secure by Letters Patent of the United States, is—

1. In a piano-action, the combination with 75 a jack, of a jack-lever pivoted to and operating said jack, and means for causing said jack-lever to push said jack during the early part of the stroke, and for causing said jack to rotate with said lever about the pivot of 80 the latter during the latter part of the stroke, substantially as described.

2. In a piano-action, the combination with 85 an abstract, of a jack-lever pivoted to the piano-frame and to said abstract, a jack operated by said jack-lever, and means for causing said jack to rotate with said lever about the pivot of the lever during the latter part of the stroke, substantially as described.

3. In a piano-action, the combination with 90 an abstract, of a jack-lever pivoted to the piano-frame and to said abstract, a jack operated by said jack-lever, an arm on said jack and an arm on said jack-lever, engaging the first arm when the hammer nears the end of 95 its stroke, substantially as described.

4. In a piano-action, the combination with 100 a jack, of a jack-lever and mechanism for operating the same, of means for causing said jack-lever to push said jack during the early 105 part of the stroke and to cause said jack to rotate with said jack-lever about the pivot of the latter at the end of the stroke, substantially as described.

5. In a piano-action, the combination with 110 a jack, of a pivoted jack-lever and mechanism for operating the same, an arm projecting from said lever, and an arm projecting from the jack and struck by the first arm toward the end of the stroke, substantially as 115 described.

6. In an upright-piano action, the combination with a hammer-butt, of a hammer-retracting spring adjusted to increase in tension approximately as the hammer retraction 115 due to gravity decreases, substantially as described.

7. In an upright-piano action, the combination with a hammer-butt, of a hammer-retracting spring adjusted to increase in tension approximately as the hammer retraction 120 due to gravity decreases, a jack engaging said hammer-butt, and a recovery-spring tending to hold said jack in engagement with said hammer-butt and acting in opposition to the 125 action of said hammer-spring, substantially as described.

8. In a piano-action, the combination with 130 a jack, a hammer-butt and a hammer, of means independent of the hammer-butt for causing the face of the jack which abuts upon the hammer to move during the direct drive in the same locus as the coacting part of the hammer-butt, and a recovery-spring carried

by said means, the force of said spring acting on the hammer-butt at a greater effective distance from the pivot of the hammer than the effective distance from the pivot of the hammer at which the force of the key operates, substantially as described.

9. In a piano-action, the combination with a hammer, a hammer-butt, a jack, and an abstract, of a jack-lever pivoted to said abstract and operating said jack, and means for causing said jack-lever to push said jack forward during the early part of the stroke, and for causing said jack to rotate in unison with said lever during the latter part of the stroke, 15 with a recovery-spring interposed between said jack and said abstract and increasing in tension as the hammer rebounds from the string, substantially as described.

10. In a piano-action, the combination with a hammer, a hammer-butt, and an abstract, of a jack-lever pivoted to the piano-frame and to said abstract, a jack operated by said jack-lever, and means for causing said jack-lever to push said jack forward during the 25 early part of the stroke, and for causing said jack to rotate in unison with said lever during the latter part of the stroke, with a recovery-spring interposed between said jack and said abstract and increasing in tension 30 as the hammer rebounds from the string, substantially as described.

11. In a piano-action, the combination with a hammer, a hammer-butt, and an abstract, of a jack-lever pivoted to the piano-frame and to said abstract, a jack operated by said jack-lever, an arm on said jack and an arm on said jack-lever, adapted to engage when the hammer nears the end of its stroke, with a recovery-spring interposed between said 35 jack and said abstract and increasing in tension as the hammer rebounds from the string, substantially as described.

12. In a piano-action, the combination with a key, an abstract operated thereby, and a 45 jack operated by said abstract, of a hammer-butt operated by said jack, a counter-check carried by said hammer-butt, and a back-check secured on said abstract and engaging said counter-check on the side next the hammer-butt, substantially as described.

13. In a piano-action, the combination with a hammer-butt and an abstract, of an arm projecting forward from said hammer-butt, a counter-check secured to said arm and inclined at an angle downward, and a back-check carried on the upper end of said abstract and engaging the face of said counter-check next the hammer-butt, substantially as described.

14. In a piano-action, the combination with a key and an abstract operated thereby, of a hammer-butt operated by said abstract, a counter-check carried by said hammer-butt, and a back-check secured on said abstract and 65 engaging said counter-check on the side next the hammer-butt, with a wire projecting from the said abstract and engaging the hammer-

butt and tending to retract the hammer when the key is released, substantially as described.

15. In a piano-action, the combination with 70 a hammer-butt and an abstract, of an arm projecting forward from said hammer-butt, a counter-check secured to said arm and inclined at an angle downward, and a back-check carried on the upper end of said abstract and engaging the face of said counter-check next the hammer-butt, with a wire projecting from the said abstract and engaging the hammer-butt and tending to retract the hammer when the key is released, substantially as described.

16. In a piano-action, the combination with a key and a substantially longitudinally movable abstract operated by said key, of a hammer operated by said abstract, and a wire from 85 said abstract adapted to strike the hammer-butt and assist in retracting said hammer-butt when the key is released, substantially as described.

17. In a piano-action, the combination with 90 a key and an abstract operated thereby, of a hammer-butt operated by said abstract, a counter-check carried by said hammer-butt, a wire extending from the end of said abstract and a back-check secured on said wire and engaging said counter-check on the side next the hammer-butt, and an adjustable screw interposed between the base of the abstract and 95 the key, substantially as described.

18. In a piano-action, the combination with 100 a hammer-butt and an abstract, of an arm projecting forward from said hammer-butt, a counter-check secured to said arm and inclined at an angle downward, a wire extending from the end of said abstract and a back-check carried on the upper end of said wire and engaging the face of said counter-check next the hammer-butt, and an adjustable screw interposed between the base of the abstract 105 and the key, substantially as described.

19. In a piano-action, the combination with 110 a key and an abstract operated thereby, of a hammer-butt operated by said abstract, a counter-check carried by said hammer-butt, and a back-check secured on said abstract and 115 engaging said counter-check on the side next the hammer-butt, an adjustable screw interposed between said abstract and said key, and a wire fastened to said key and holding said abstract in engagement with said screw, substantially as described.

20. In a piano-action, the combination with a hammer-butt, and an abstract, of an arm projecting forward from said hammer-butt, a counter-check secured to said arm and inclined at an angle downward, and a back-check carried on the upper end of said abstract and engaging the face of said counter-check next the hammer-butt, an adjustable screw interposed between said abstract and 125 said key, and a wire fastened to said key and holding said abstract in engagement with said screw, substantially as described.

21. In an upright-piano action, the combi-

nation with a hammer acted upon by gravity with a variable retraction, of a hammer-retracting spring also acting upon said hammer, the parts being so arranged that the total 5 hammer retraction shall be approximately constant, mechanism for driving said hammer toward the spring, means for terminating the said driving relation between said mechanism and said hammer, and a spring 10 for restoring said relation, substantially as described.

22. In a piano-action, the combination of 15 a key with operating mechanism driven thereby, and an arm of said key extending over a portion of said operating mechanism and tending to prevent separation of said mechanism from said key, substantially as described.

23. In a piano-action, the combination with 20 a key, of an abstract operated thereby, and a hammer operated by said abstract with a wire of said abstract adapted to aid the return of the hammer to the initial position, substantially as described.

24. In a piano-action, the combination with 25 a key, of a lever, an operating-bar pivoted to said lever, a link pivoted to the operating-bar and to the piano-frame, and an arm attached to the key limiting the separation of said key and operating-bar, substantially as described.

25. A hammer-spring for use in piano-actions having a flat tapering body with an enlarged flat head, substantially as described.

26. In a piano-action, the combination with 30 a rail, a flat spring secured to said rail, and a hammer-butts provided with a pointed nose engaging the other end of said spring, substantially as described.

27. In a piano-action, the combination with 35 a rail, a flat spring having a tapering body and a flat head secured at the tail end to said rail, and a hammer-butts provided with a nose engaging said enlarged head, substantially as described.

28. In a piano-action, the combination with 40 the hammer-rail, of a flange secured to said rail, a damper-spring having a base portion p^5 secured to said rail by the flange-screw c^7 and a spring portion p' to bear against the nose of 45 the damper-lever, substantially as described.

29. In a piano-action, the combination with 50 a hammer spring-rail and a separate padded rail for the dampers secured thereto and adjustable independently thereof, substantially as described.

30. In a piano-action, the combination with 55 a jack, of a pivoted jack-lever and mechanism for operating the same, means for causing said jack-lever to push said jack forward 60 during the early part of the stroke, and to cause the jack to rotate in unison with the jack-lever toward the end of the stroke, substantially as described.

31. In a piano-action, the combination with 65 a hammer spring-rail and a plurality of springs secured thereto, of means for rocking said rail to vary the tension of the springs

on the hammers, comprising a nose attached to the action-frame and forming a fulcrum for the rail, and adjusting-screws on opposite 70 sides of said fulcrum, substantially as described.

32. In a piano-action, the combination with the hammer-rail, of a flange secured to said rail recessed on the top, of a damper-spring 75 having a base portion p^5 to fit in said recess, and a spring portion p' to bear against the nose of the damper-lever, substantially as described.

33. In a piano-action, the means for adjusting 80 the rail B comprising the slotted flange R attached to or integral with the action-frame, and provided with the hole r^2 , retaining-screws passing through said slots, and a dowel-pin driven through said hole into said 85 rail when the same has been adjusted, substantially as described.

34. In a piano-action, a removable frame having the front toe or edge of its supporting-base rearward of a line drawn through the 90 point of driving contact between the key and operating mechanism, substantially as and for the purposes described.

35. In a piano-action, the combination with 95 a key and an abstract operated thereby, of a hammer-butts operated by said abstract, a capstan-screw in said key beneath the foot of said abstract, and an arm from said key extending over the foot of said abstract, substantially as described.

36. In a piano-action the combination with 100 a key, an abstract operated by said key and hung so that it will move upwardly and forwardly, a jack operated by said abstract, a recovery-spring on said abstract acting on 105 said jack, causing the upper end of the latter to move with the abstract thereby restraining it to approximately the same locus as the co-acting part of the hammer-butts until release commences; of a hammer-butts and hammer 110 operated by said jack, substantially as described.

37. In a piano-action the combination with 115 a key, an abstract operated by said key, a jack-lever supporting the upper end of said abstract, a link supporting the lower end of said abstract, causing the abstract to move upwardly and forwardly when operated on by the key, a jack pivoted on the said jack-lever, a recovery-spring on the said abstract 120 connected with the said jack, causing the upper end of the latter to move with the abstract thereby restraining it to approximately in the same locus as the coacting part of the hammer-butts until release commences; of a 125 hammer-butts and hammer operated by said jack, substantially as described.

In testimony whereof I affix my signature in presence of two witnesses.

JOHN W. DARLEY, JR.
